UNITED STATES PATENT OFFICE

OSCAR SANDBERG, OF BATTLE CREEK, MICHIGAN, ASSIGNOR TO JOHNSON AUTOMATIC SEALER CO., LTD., OF BATTLE CREEK, MICHIGAN, A PARTNERSHIP ASSOCIATION LIMITED OF MICHIGAN

WRAPPING MACHINE

Application filed April 27, 1929. Serial No. 358,661.

This invention relates to wrapping machines, and while capable of general use, is particularly adapted for wrapping packages or the like fed by hand into the machine.

One object of the invention is to provide a wrapping machine having improved devices for wrapping the packages as they are advanced automatically through the machine.

Another object of the invention is to provide a wrapping machine having improved wrapping devices mounted on the package advancing means and acting on each package while it is being advanced by said means.

Another object of the invention is to provide a wrapping machine having improved wrapping devices past which the packages are advanced after being acted upon by the wrapping devices mounted on the package advancing means.

Another object of the invention is to provide an improved wrapping machine which is simple in construction, inexpensive to manufacture, install, and maintain in operation, and readily adapted for the needs of manufacturers of various classes of packaged goods.

These and other objects of the invention will appear as the following description thereof proceeds, and in order to more clearly understand the invention, reference may be had to the appended drawings which illustrate one embodiment of the inventive idea.

In said drawings—

Fig. 1 is a side elevation of a wrapping machine embodying the present invention;

Fig. 2 is a top plan view of the machine shown in Fig. 1;

Fig. 3 is a transverse vertical sectional view, with parts omitted, on the line 3—3 of Fig. 1;

Fig. 4 is a transverse vertical sectional view, with parts omitted, on the line 4—4 of Fig. 1;

Fig. 5 is an enlarged side elevation of a rear end folder in its raised or operative position;

Fig. 6 is a detail perspective view of two packages in wrapped and unwrapped conditions, respectively;

Fig. 7 is a side elevation of a rear end folder in its lowered or inoperative position;

Fig. 8 is a top plan view of the folder shown in Fig. 7;

Fig. 9 is a detail perspective view of part of the operating mechanism for folder shown in Figs. 7 and 8;

Fig. 10 is a detail perspective view of upper and lower end folders shown in Figs. 1 to 3, inclusive; and

Fig. 11 is a side elevation of the upper and lower end folders, showing part of the operating mechanism therefor.

Referring to the drawings, wherein like reference characters designate like parts throughout the several views, said drawings show the machine framework, driving mechanism mounted thereon, package advancing means, rear end folders, upper and lower end folders, front end folding and package sealing devices, and package cooling devices. These instrumentalities will be described in the order named and are preferably operated and constructed as follows.

Machine framework—Figs. 1 to 3, inclusive

The various movable parts of the wrapping machine are preferably mounted on a framework comprised by rectangular frames 5, 6 which are supported on legs, such as indicated at 7, 8, that are bolted or otherwise suitably secured at 9, 10, respectively, to the machine foundation 11. The frames 5, 6 are connected together at the top thereof by cross members or yokes 12, 13. These yokes are bolted at 14, 14 and 15, 15, respectively, to the side frames 5, 6, to yoke 12 having secured thereto at 16, 16, a pair of spaced package supporting rails 17, 17 which extend longitudinally of the machine and have their front projecting ends supported on the cross member or yoke 13 thereof.

Secured at 16, 16 and 18, 18 on the rails 17, 17 at the rear thereof, is a feed table 19 from which packages 20 may be fed by hand onto the rails 17, 17 to be pushed therewith by package advancing mechanism hereinafter described.

Each package 20 has folded therearound a wrapper 20 that is overlapped on the bottom of the package to provide a seam 22 which may be sealed, if desired, before the package is fed into the machine.

The condition of each package before introduction into the machine is illustrated, for

example, in Fig. 4 at the left thereof, wherein it will be noted that the wrapper 21 projects from both ends of the package to form lower, rear, upper and front projecting end portions 23, 24, 25 and 26, respectively. The packages advanced along the rails 17 by the package advancing mechanism, are engaged by a top rail 27 that is provided with vertical standards 28. These standards project upwardly through suitable openings formed in the horizontal arms 29 of brackets that have their vertical arms 30 bolted or otherwise suitably secured at 31 on the side frame 5 of the machine. The top rail 27 is adjustably supported on said brackets by collars 32 which rest on the top of the bracket arms 29 and may be secured in any position of adjustment on the standards 28, as by thumb screws 33.

Driving mechanism—Figs. 1 to 3, inclusive

Bolted or otherwise suitably secured, as at 34, on the side frame 6 of the machine, is a support 35 for an electric motor 36. The motor 36 serves to drive the various movable parts of the machine and said motor, and therefore said parts may be controlled by a switch, or by a clutch, or by both, in a manner well understood in the art and requiring no detail description and illustration. By way of example, however, a control for the motor is shown in the form of a switch 37 bolted or otherwise suitably secured to the machine framework and interposed in a feed line 38, 39 for supplying electrical current to the motor from any suitable source.

Fixed on the armature shaft 40 of the motor 36, is a pulley 41 around which passes a belt 42. The belt 42 also passes around a pulley 43 which is fixed on a shaft 44 extending transversely of the machine and journaled in suitable bearings on the framework thereof. Fixed on the shaft 44 is a sprocket 45 around which passes a chain 46 that also passes around a sprocket 47. Tension on the chain 46 may be regulated as desired, by a sprocket 48 engaged with said chain and journaled on an arm 49. The arm 49 is adjustably pivoted at 50 on the machine framework which has connected therewith one end of a spring 51 that has its opposite end connected with the arm 49 to yieldingly urge the sprocket 48 against the chain 46 and thereby maintain tension on the same.

The sprocket 47 is loosely mounted on a rockshaft 52 which extends transversely of the machine and is journaled in suitable bearings on the framework thereof. Fixed on or formed integrally with the sprocket 47, is a sleeve 53 through which the rockshaft 52 projects loosely into its bearing at the adjacent side of the machine. Fixed on the sleeve 53 is a sprocket 54 around which passes a chain 55. The chain 55 also passes around a sprocket 56, and tension may be maintained on said chain by a sprocket 57 which en-

gages the chain and is adjustably mounted in a bracket 58 bolted or otherwise suitably secured to the machine framework. The sprocket 56 is fixed on a shaft 59 which extends transversely of the machine and is journaled in suitable bearings on the framework thereof. The various movable parts of the machine that act on the packages, are connected with this shaft which thus form the main driving shaft for said parts.

Package advancing mechanism—Figs. 1 to 3, inclusive

The package advancing mechanism is preferably of the type disclosed in my co-pending application Serial No. 356,565 filed April 19, 1929, and is operated and constructed as follows. Fixed on the shaft 59 is a cam 60, in the groove 61 of which is engaged a roller 62. This roller 62 is journaled at 63 on a link 64 provided at one end with a fork 65 that is engaged over the shaft 59. The opposite end of the link 64 is pivotally connected at 66 with one arm 67 of a bell crank 68 provided with a second arm 69. The bell crank 68 and a second bell crank 68' having arms 67' and 69', are loosely mounted in spaced relation on a stay shaft 70 extending transversely of the machine at the front end thereof and secured to the machine framework in any suitable manner. A second stay shaft 71 extending transversely of the machine at the rear thereof and secured to the machine framework in any suitable manner, has loosely mounted thereon in spaced relation, a pair of bell cranks 72, 72' provided with arms 73, 74 and 73', 74', respectively.

The arms 73 and 67 of the bell cranks 72 and 68 are pivotally connected at 75 and 66, respectively, by a link 77. The arms 67' and 73' of the bell cranks 68' and 72' are pivotally connected at 76 and 78, respectively, by a link 79. The arms 73' and 67 are also pivotally connected at 78 and 66 with the link 64 which extends diagonally across the machine to said arms. It will thus appear that by the described connections for the several bell cranks with the cam 60, said bell cranks will be rocked in opposite directions during the operation of the machine. These bell cranks carry a rocking frame for raising and lowering the package advancing means, said frame being comprised by side members 80, 81 having legs 82, 83, respectively. The legs 82 of the side member 80 are pivotally connected with the bell crank arms 69 and 74, and the legs 83 of the side frame member 81 are pivotally connected with the bell crank arms 69' and 74'.

Fixed on the shaft 59 at one end thereof, is an arm 84, the free end of which is pivotally connected at 85 with one end of a link 86. The opposite end of the link 86 is pivotally connected at 87 with a bar 88 mounted on and adjustable lengthwise of a frame member 89,

as by pin and slot connections 87, 90 and 91, 92, respectively. The frame member 89 is mounted for horizontal reciprocating movement in guides 93 formed on the legs 82 of the rocking frame member 80. The frame member 89 and the bar 88 are reciprocated together on the rocking frame member 80, by the described connections for said bar with the arm 84 on shaft 59. Bolted or otherwise suitably secured on the bar 88, are brackets 94 that have connected therewith, as by bolts 95, 96, a front cross member 97 and a bracket-like rear cross member 98, respectively. The cross members 97, 98, are bolted or otherwise suitably secured, as at 99, 100, to the opposite ends of a frame member 101 slidably mounted on the frame member 81. The frame members 89, 101, and the cross members connecting the same, thus constitute a slidable frame mounted on the rocking frame 80, 81, and reciprocated therealong by the described connections for the frame member 89 with the arm 84 on shaft 59.

Bolted or otherwise suitably secured on the cross members 97, 98 of said sliding frame, are a pair of spaced bars 102 that extend longitudinally of the sliding frame. The bars 102 have adjustably mounted thereon at intervals, transversely aligned package advancing members 103, 103', 103'' which, through the action of the rocking and sliding frames, repeatedly move upwardly, forwardly, downwardly, and rearwardly relative to the package supporting rails 17, to thereby advance packages along said rails. It will thus appear that the sliding frame moves continuously in a closed or orbital path, and that the package advancing devices are likewise moved in similar paths.

D. Rear end folders, Figs. 1 to 5 inclusive, and 7 to 9 inclusive

In accordance with the present invention, the rear end folders, which act to fold in the rear projecting end portions 24 of the wrappers on the packages, are carried by the package advancing means to move therewith and relatively thereto. The rear end folders 104, two in number, are bolted or otherwise suitably secured at 105, on the front ends of links 106 that are pivotally connected at 107 with levers 108. The levers 108 are fixed on rock-shafts 109 that extend transversely of the machine. These rock shafts are journaled in suitable bearings on the frame member 89 and one of the bars 102, respectively, each of which moves continuously in a closed or orbital path. The rockshaft bearings on frame member 89 are formed in said member and in a bracket 89' bolted or otherwise suitably secured thereto. The rockshaft bearings on the aforesaid bar 102 are formed in a bracket 102' (Fig. 4) bolted or otherwise suitably secured to said bar and projecting downwardly and rearwardly therefrom.

The links 106 and the levers 108 constitute with the brackets 89' and 102', quadrilateral linkage systems that are expanded and collapsed to operate the folders 104 as follows. One pair of the levers 108, has secured to or formed integrally therewith, arm 110 on which are journaled rollers 111 (Fig. 4).

During forward movement of the package advancing means, a package positioned on the rails 17 in front of the package advancing members 103 is advanced thereby along said rails, and the rollers 111 engage cams 112 which swing the folders 104 upwardly and forwardly so that they fold in the rear projecting end portions 24 of the wrapper on said package. The cams 112 are pivotally mounted at 113 on plates 114 that stand vertically and are bolted or otherwise suitably secured, as at 115, on vertical arms 116 of brackets 117. The brackets 117, in turn, are bolted or otherwise suitably secured to the side frames 5 and 6 of the machine, and said brackets have projecting inwardly therefrom pins 118 for supporting the pivoted cams 112 in inclined positions. The lower ends of the cams 112 are curved downwardly to facilitate engagement of the rollers 111 therewith, and forwardly of the front ends of said cams, and in spaced relation therewith, are tracks 119 down which the rollers 111 travel after they have passed off the front ends of the cams. The tracks 119 are secured to, or formed integrally with, the plates 114 and project laterally and inwardly therefrom, as clearly shown in Figs. 4 and 8.

When the folders 104 have folded in the rear projecting end portions 24 of the wrapper on a package as aforesaid, the package advancing means is lowered, retracted, and moved upwardly to advance the next package. The forward movement of the package advancing means disengages the rollers 111 from the upper front ends of the cams 112, and during lowering movement of the package advancing means, the rollers travel down the tracks 119 and the folders 104 are swung rearwardly and downwardly by a spring 120 (Figs. 5, 7 and 8). This spring 120 has its opposite ends connected with one of the arms 108 and an arm 121, respectively. The arm 121 extends rearwardly and downwardly from the bracket 89' and is bolted or otherwise suitably secured thereto. During rearward movement of the package advancing means, the rollers 111 engage the lower, curved ends of the pivoted cams 112 and swing said cams upwardly out of the path of movement of said rollers and the arms 110.

Lower and upper end folding devices—Figs. 1 to 3, inclusive, 10 and 11

When the package advancing means is lowered, the package is left in position on the rails 17 to be end folded by the lower and 130

upper end folders 122 and 123, respectively. These folders are preferably operated and constructed as follows. Fixed on the shaft 59 is a cam 124, in the groove 125 of which is engaged a roller 126. This roller 126 is journaled on a lever 127 that is pivoted at 128 on a bracket 129, bolted or otherwise suitably secured to the machine framework at the rear and top thereof. The free end of 10 the lever 127 is pivotally connected as at 130, with one extremity of a two-part link 131 the parts of which are adjustably connected together, as by pin and slot connections 132, 133. The opposite extremity of 15 the link 131, is pivotally connected at 134 with the free end of an arm 135 that is fixed on the rockshaft 52.

Fixed on the rockshaft 52 are arms 137. One of the arms 137 has connected therewith 20 one extremity of a spring 136 that has its opposite end connected with the machine framework. The arms 137 are arranged in pairs spaced apart on the rockshaft 52, the arms of each pair being secured on said rockshaft 25 approximately 180° apart. The free ends of the arms 137 are pivotally connected at 138 with the lower extremities of links 139. The upper extremities of the links 139 are pivotally connected at 140, with the lower ends 30 of slides 141 that are mounted for vertical reciprocating movement in guides 142 bolted or otherwise suitably secured to the machine framework at the top thereof. The folders 122 are mounted on the upper ends of the 35 slides 141 and are adjustable vertically thereon. For this purpose, the folders 122, 123 are bolted or otherwise suitably secured at 142' (Fig. 10) on brackets 143 which are secured to the slides 141, as by pin and slot 40 connections 144, 145, respectively.

The folders 122, 123 have opposed inner ends 122', 123', that are curved or bent outwardly toward the opposite sides of the machine to initially engage the projecting lower 45 and upper end portions 23, 25 respectively of the wrapper on the package. The folders 122 are set somewhat closer to the package than the folders 123. When the package has 50 been positioned in line with said folders, they are moved by the described connections therefor with the cam 124, toward each other so that the folders 122 fold in the end projecting portions 23 of the wrapper on the rear 55 folded portions 24 thereof and the folders 123 fold in the upper projecting end portions 25 of the wrapper on the folded portions 23 of said wrapper. The operating mechanism for the folders 122, 123, then 60 moves them away from each other out of engagement with the package, whereupon the package advancing means rises to engage the pushers 103' with said package. At the same time the pushers 103 are engaged with a second package that has been positioned on the 65

rails 17 to be advanced and have the rear projecting end portions 24 of the wrapper folded, as before described.

Front end folders and package sealers, and package cooling devices, Figs. 1 to 3, inclusive 70

When the second package is advanced by the pushers 103, to the folders 122, 123, the first package is advanced by the pushers 103' 75 between end plates 146 that fold in the front projecting end portions 26 of the wrapper and seal the package. The folding and sealing plate 146 extend rearwardly of cooling devices on plates 147 and are provided with 80 heating devices 148 which preferably comprise resistance elements secured to the plates 146 in any desired manner and connected by lead wires 149, 150, with any suitable source of electrical current. The plates 146 and 147 85 are mounted on spaced brackets or the like 151 (Fig. 2), that extend longitudinally of the machine and are adjustably mounted, as at 152, on the front cross member or yoke 13.

When the first and second packages are 90 advanced by the pushers 103', 103, respectively, the first package is finally folded and sealed by the plates 146 and the second package, the rear projecting wrapper portions 24 of which have been folded by the folders 95 104, is left in position where the lower and upper end folders 122, 123 may fold in the lower and upper projecting wrapper portions 23, 25, as previously described. The package advancing means then lowers again and 100 moves rearwardly during the folding operation of the folders 122, 123. These folders are then moved apart whereupon the package advancing means raises to engage the pusher fingers 103'', 103', and 103, with the 105 first, second, and a third package respectively. The third package has previously been fed from the table 19 onto the rails 17, to be engaged by the pushers 103 as aforesaid.

The package advancing means then moves 110 forwardly and the pushers 103'' deliver the first package from the machine past the cooling plates 147, and pushers 103' advance the second package between the plates 146 to be 115 finally folded and sealed thereby, and the pushers 103 advance the third package to a position in line with the folders 122, 123. During travel of the third package toward 120 said folders, the rear projecting wrapper portions 24 thereof are folded by the folders 104, as in the case of the first and second packages. The above mentioned operations are repeated as the packages are fed in succession from the table 19 onto the rails 17, and 125 each package fed from said table to the rails 17 may, if desired, be registered with respect to the devices in advance of the package by any suitable means for this purpose (not shown). 130

Operation

The operation of the machine will be clearly understood from the foregoing, and may be briefly summarized as follows. The packages fed successively from the table 19 onto the rails 17, are each engaged successively by the pushers 103, 103', 103'', which advance the packages in succession past the folders 122, 123, the folders and sealers 146, and the cooling plates 147, for delivery from the machine. Each package advanced by the pushers 103 is engaged by the folders 104 which fold in the rear projecting end portions 24 of the wrapper. The folders 122, 123 act, as before described, to fold in the lower and upper projecting end portions 23, 25 of the wrappers on the packages, and the folding and sealing plates 146 finally fold and seal each package advanced there past. The cooling plates 147 engage the sealed ends of the heated packages to cool the same as they are successively advanced past said plates for delivery from the machine.

While one embodiment of the inventive idea is herein illustrated and described with more or less particularity, it is to be expressly understood that the invention is not limited to said embodiment, or otherwise than by the terms of the appended claims.

What is claimed is:

1. In a machine of the character described, means for advancing a package with a wrapper thereon to be folded, a quadrilateral linkage carried by said means, a folder mounted on said linkage to move with and relative to the package advancing means, and means for operating the quadrilateral linkage whereby said folder may fold the wrapper on said package.

2. In a machine of the character described, package advancing means, a quadrilateral linkage carried thereby, a folder mounted on the quadrilateral linkage to move therewith and swing relative to the package advancing means, and means for expanding or opening said linkage whereby said folder may fold a wrapper on a package being advanced by said advancing means.

3. In a machine of the character described, means for advancing a package with a wrapper thereon to be folded, a quadrilateral linkage carried by said means, a wrapper folder mounted on said linkage to move therewith and relative to the package advancing means, means for imparting motion to the package advancing means, and means for operating said linkage and the wrapper folder during movement of said package advancing means.

4. In a machine of the character described, means for advancing a package having a wrapper thereon projecting from one end of the package, a quadrilateral linkage carried by said means, a wrapper folder mounted on one element of the linkage to move therewith

and relative to the package advancing means, and means for expanding and collapsing said linkage whereby the folder may fold a projecting end of the wrapper on said package and thereafter recede therefrom.

5. In a machine of the character described, means for advancing a package with a wrapper thereon to be folded, a folder pivotally mounted on said advancing means to move bodily therewith and swing relative thereto, means for swinging said folder in one direction to fold a part of the wrapper on said package, a pair of spaced folders adapted to be reciprocated toward and away from each other transversely of the path of movement of the package, and means for reciprocating said pair of folders to fold other parts of the wrapper on the package.

6. In a machine of the character described, means for advancing a package with a wrapper thereon to be folded, a folder mounted on said advancing means to move therewith and relative thereto, means for operating said folder to fold a part of the wrapper on the package, a pair of spaced folders movable toward and away from each other transversely of the path of movement of the package, and means for reciprocating said pair of folders to fold other parts of the wrapper on the package.

7. In a machine of the character described, means for advancing a package having a wrapper thereon projecting from one end of the package, a folder for folding a rear projecting end portion of the wrapper on the package, means for pivotally mounting the folder on the package advancing means to move bodily therewith and swing relative thereto, operating mechanism for the last named means and said folder, a pair of spaced folders for folding bottom and top projecting end portions of the wrapper on the package, and means for reciprocating said pair of folders bodily toward and away from each other.

8. In a machine of the character described, a movable member, a pair of levers pivoted thereon, a link pivotally connected with said levers, a folder mounted on said link, and means for moving the levers and the link together in opposite directions during movement of said member whereby the folder is swung upwardly and forwardly and then rearwardly and downwardly relative to the movable member.

9. In a machine of the character described, a member moving in a closed or orbital path, a folder, devices mounted on the member and carrying the folder for movement with the member, and means for operating said devices and said folder to raise, advance, retract, and lower the same during movement of said member.

10. In a machine of the character described, a member moving in a closed or or-

bital path, a folder, means pivotally mounted on the movable member and carrying the folder for movement with the member, and devices for swinging said means and the folder together in opposite directions during movement of said member.

11. In a machine of the character described, a member moving in a closed or orbital path, a quadrilateral linkage carried by said member and adapted to be expanded and collapsed, a folder carried by the linkage, and means for expanding and collapsing the linkage to move the folder upwardly and forwardly and then rearwardly and downwardly during movement of the linkage and the folder with said member.

12. In a machine of the character described, a movable member, means for moving the same, a linkage carried by and movable with the member and adapted to be expanded and collapsed, a folder mounted on the linkage to travel therewith, and means for expanding and collapsing the linkage to swing said folder in opposite directions.

13. In a machine of the character described, a moving member, a linkage carried by and movable with the member and adapted to be expanded and collapsed, a folder mounted on the linkage to travel therewith and move in opposite directions relative to the moving member, and means for expanding and collapsing the linkage to move the folder in opposite directions.

14. In a machine of the character described, a member moving in a closed or orbital path, a linkage carried by and movable with the member and adapted to be expanded and collapsed, a folder pivoted on the linkage to travel therewith, a cam for expanding the linkage to swing the folder in one direction, and a spring for collapsing the linkage to swing the folder in the opposite direction.

15. In a machine of the character described, a moving member, a linkage carried by and movable with the member and adapted to be expanded and collapsed, a folder mounted on the linkage and carrying a cam engaging element, a cam on which the cam engaging element travels during movement of the member and adapted to expand the linkage and move the folder in one direction, and means for collapsing the linkage and moving the folder in the opposite direction when said element is disengaged from the cam.

16. In a machine of the character described, a movable member, a folder pivoted thereon, a pivotally mounted cam, a device on the folder engaged by the cam to swing the folder in one direction on forward movement of the movable member, and means for moving the folder in the opposite direction adapted to position said device so that it engages and swings the cam on rearward movement of said member.

17. In a machine of the character described, a movable member, a folder pivoted thereon, a pivotally mounted cam, a roller on the folder engaged by the cam to swing the folder in one direction on forward movement of the movable member, a spring for moving the folder in the opposite direction and adapted to position said roller so that it engages and swings the cam on rearward movement of said member, and a track for the roller on which it travels before engaging the cam to swing the same.

18. In a machine of the character described, a movable member, a folder pivoted thereon, a pivotally mounted cam, a support for the cam disposed at one side of its pivot, a roller on the folder engaged by the cam to swing the folder in one direction on forward movement of the movable member, and means for moving the folder in the opposite direction adapted to position said roller so that it engages and swings the cam on rearward movement of said member.

19. In a machine of the character described, a movable member, means for moving the member, a linkage carried by and movable with the member, a folder mounted on the linkage to move therewith and relative to the member, and means for moving the linkage and the folder during movement of said member.

20. In a machine of the character described, a rocking member, a sliding member thereon, means for imparting rocking and sliding movements to said members respectively, a folder mounted on the sliding member to move therewith and relative thereto, and means for moving the folder during movement of said sliding member.

21. In a machine of the character described, a pair of folders, a pair of juxtaposed slides each carrying one of said folders, a rockshaft, a pair of arms fixed on the rockshaft approximately 180° apart, a pair of links each having its opposite ends pivotally connected with one of said arms and one of the slides, and means for rocking said shaft to reciprocate the slides in opposite directions respectively and move the folders toward and away from each other.

22. In a machine of the character described, a pair of aligned folders movable toward and away from each other, a rocking and sliding member extending substantially at right angles to the path of movement of said folders, and another folder mounted on the rocking and sliding member to move therewith and relative thereto.

In testimony whereof I have signed this specification.

OSCAR SANDBERG.
